UNITED STATES PATENT OFFICE.

WILLIAM BELL, OF VERONA, MISSISSIPPI.

FENCE.

SPECIFICATION forming part of Letters Patent No. 349,559, dated September 21, 1886.

Application filed April 7, 1886. Serial No. 198,118. (No model.)

To all whom it may concern:

Be it known that I, WILLIAM BELL, a citizen of the United States, residing at Verona, in the county of Lee and State of Mississippi, 5 have invented a new and useful Improvement in Fences, of which the following is a specification.

The object of my invention is to produce a combined frame and wire fence, which shall 10 possess sufficient strength, without the use of barbs, to repel stock.

The fence is constructed with horizontal and vertical wires firmly tied at their intersections, and with diagonal wires, which are also similarly tied at their intersections to the horizontal wires and to each other. As a finish and 15 for additional strength a top rail is also employed.

In order that the invention may be fully understood, I will proceed to describe it with reference to the accompanying drawing, which represents an elevation of my improved fence.

The horizontal wires 1 are fixed, by nails or staples 2, to rigid wood or metal posts 3, and 20 are arranged at any desired distance asunder. Spaced suitably between the posts 3, and connected to the horizontal wires 1 by wire ties 4, are vertical wires 5, which take the place of palings.

25 6 6 are diagonal braces, fixed by nails or staples to the tops and bottoms, respectively, of alternate posts, in such manner that they will cross each other at center. At their

points of crossing they are tied with wire 8, which may also unite them to the upright 35 wires 5 at those points. Similarly the diagonal wires are tied at 9 9 to the horizontal wires 1.

The top rail, 10, connects the posts 3, for increasing at the same time the rigidity and ornamental effect. 40

I am aware that, broadly considered, it is not new to construct fences with horizontal wires, vertical wires, or pickets, or diagonal wires extending from the top of one post to 45 the bottom of the next post, and vice versa, separately considered.

Having thus described my invention, the following is what I claim as new therein, and desire to secure by Letters Patent: 50

A combined frame and wire fence consisting of posts 3, having staples 2, continuous horizontal wires threaded through the post-staples, vertical wires 5, diagonal wires 6, extending from the bottom of one post to the 55 top of the next post, and vice versa, fastenings 8, securing the crossed diagonal wires at their intersection, fastenings 9, securing the diagonal wires to the horizontal wires, and fastenings 4, securing the vertical wires and 60 horizontal wires together, all substantially as shown and described.

WILLIAM BELL.
